UNITED STATES PATENT OFFICE.

MCLEOD THOMSON, OF ATLANTIC CITY, NEW JERSEY, ASSIGNOR TO THE RAIL JOINT COMPANY, OF NEW YORK, N. Y., A CORPORATION OF NEW YORK.

CONVERTIBLE RAIL-JOINT STRUCTURE.

Application filed June 16, 1927. Serial No. 199,321.

This invention relates to an improvement in rail joint structures, and more particularly to a structural formation adapting the joint bar for the usual flat head-fishing engagement, and also adapting it to function as a head-free type of bar wherein the bearing and loading engagement is focused in and at the head fillet of the rail.

To that end the present invention contemplates what may be termed a convertible rail joint structure which, in its preferred use, has an initial head-fishing bearing, and, as wear progresses and the bar is adjusted under the tightening action of high tensile bolts, it ultimately assumes and takes a permanent head-free bearing and loading engagement at the head-fillet of the rail.

Also, the present invention provides a rail joint bar adaptable to two rails of different fishing or to the difference in fishing of a new rail and a worn rail of the same section. This assures a proper fit under different conditions of fishing.

A general object of the invention is to provide a convertible rail joint structure satisfactorily meeting the requirements for an initial head-fishing bearing preliminary to taking on the desirable functions of a head-free rail joint with all of the attendant advantages thereof both with respect to satisfactory maintenance and durability of the joint.

The special feature of the invention is necessarily susceptible of structural modification without departing from the spirit or scope thereof, but a preferred and practical embodiment is shown in the accompanying drawings, in which:—

Figure 1 is a sectional view illustrating the primary or initial position of the joint bar when it is first applied to the rail and takes a flat fishing engagement with the head-fishing bearing at the underside of the rail head.

Figure 2 is a similar view showing the ultimate seating of the bar in the head fillet of the rail, under wear and adjustment, thereby functioning entirely as a head-free rail joint.

Figure 3 is a cross-sectional view of a complete rail joint embodying the invention and illustrating by full and dotted lines the progressive action of the bar as it is rotated under adjustment from a head-fishing engagement to a rail fillet engagement.

Figures 4 and 5 are a pair of similar views illustrating the adaptability of the convertible bar to rails of different fishing height.

Similar reference characters designate corresponding parts throughout the several figures of the drawings.

In carrying forward the present invention no alteration is required in the shape of the standard rail designated in the drawing by the numeral 1 and including the usual head 2, the base flange 3 and the connecting web 4. The rail head is provided at its underside with the usual flat head fishing surface 5 and at the juncture of such surface with the web of the rail the latter is formed with the usual rounded fillet 6 which, in the present invention may be utilized as a bearing socket when the structure functions as a head-free rail joint of the general type disclosed in the reissue patent of W. P. Thomson No. 15,773, granted February 19, 1924.

The convertible joint bar having the dual function contemplated by the present invention is designated generally by the reference letter B and includes as principal elements thereof a head member 7, the foot flange member 8 and the connecting bar web 9. These are the usual elements of a joint bar of the angle type, and it is the purpose of the present invention to provide a joint bar of this type, or of any other acceptable type, with bearing elements adapting it for a head-fishing engagement with the rail, or for a head-fillet engagement with the rail to provide, in the latter case, a head-free type of rail joint. To that end the head member 7 of the joint bar is provided at its upper face with an inclined flat head-fishing bearing 10 whose angle corresponds to the angle of the head-fishing surface of the rail head when it engages such surface.

In addition, the said head member 7 of the bar is further provided, at its inner corner, with the rounded or curved fillet engaging element of ball 10⁴ adapted to have an anchorage in and against the fillet bearing 6 of the rail when the foot of the bar has been rotated a sufficient distance inward by the tightening of the high-tensile joint bolts 11 to take up the wear.

In the embodiment of the invention shown in Figs. 1, 2 and 3 of the drawings the lower member 8 of the joint bar is shown provided with a flange bearing surface 12 which is adapted, under wear and adjustment, to

move inwardly and upwardly on the rail base flange 3 and as material wear will occur, in the use of the joint, in and over that portion of the rail flange engaged by 5 the foot member of the joint bar, the latter ultimately, as plainly shown in Fig. 2 of the drawings, will accommodate itself to the wear in the rail base flange so that the fillet engaging element 10^a of the joint bar will 10 firmly seat or anchor itself in the fillet bearing socket 6 of the rail. This makes a head-free rail joint having the functions and advantages of that type of joint originating with the Thomson reissue patent referred to. 15 Thus, it will be seen that the dual characteristic of the rail joint bar B renders the same convertible from one type of joint to another.

The action of the convertible bar, under 20 the influence of the high-tensile bolts 11, is well exemplified in Fig. 3 of the drawings, wherein the full line positions of the bars show the initial flat fishing engagement thereof respectively with the undersides of 25 the rail heads, and the upper sides of the rail flanges, while the two dotted line positions illustrate the progressive movement of the bars, under wear and adjustment, by a rocking or oscillation inward of the lower 30 portions of the bar over the rail flanges until the ultimate head-free rail joint results.

Another phase of the invention, indicating its scope, is that illustrated in Figs. 4 35 and 5 of the drawings, showing the joint bar adapted to a plurality of rails which may differ in fishing height, or in the angles of the fishing bearings, or both, or to the difference in fishing of a new rail and a worn 40 rail of the same section. To better adapt the joint bar for that purpose the same is provided in addition to the top head-fishing bearing 10 and the fillet engaging element 10^a, with a pair of separate angularly related flange bearing faces 13 and 14 formed 45 on the lower side of the bar, and either of which flange bearing faces is adapted to have a fishing engagement with the upper side of the rail flange, according to the use 50 of the bar. In both Figs. 4 and 5 of the drawings the outlines of two rails respectively of different fishing height and differing in the angles of the fishing bearings are shown by full and dotted lines. This is a 55 condition which occurs not only with new rail, but when a railroad re-rolls some of its rail. The present invention accommodates itself to that condition, and referring to the example shown in Fig. 4 the full line rail 60 is illustrated as having the greater fishing height and the dotted line rail as having the lesser fishing height. Accordingly, in adapting the invention to either of these conditions it will be observed that with the full 65 line rail shown in Fig. 4 the joint is a head-

free joint only, but when the joint bar is used in connection with the dotted line rail of Fig. 4 the bar initially has both head-fishing and fillet bearing, and rotates, under wear and adjustment, to a head-free position. 70

In Fig. 5 of the drawings the full lines show the rail of the lesser fishing wherein the joint bar has a head-fishing contact initially with a clearance from the rail head 75 fillet. In such use of the bar the same progressively rotates, under wear and adjustment, to a head-free position. Also, Fig. 5 shows by the dotted line rail a condition where the same bar will have a head-free 80 position initially and permanently.

From the foregoing it is thought that the construction and use of the improved bar as a rail joint structure will now be readily appreciated by those familiar with the art without further description and it will be understood that changes in the form, proportion and minor details of construction may be resorted to without departing from the spirit 85 and scope thereof. 90

I claim:—

1. A convertible rail joint structure including the rail having a head-fishing surface and a bearing-socket at its fillet and a joint bar having a head-fishing bearing 95 adapted to engage and to be freed from the head-fishing surface of the rail and with a fillet engaging element adapted to engage said bearing socket.

2. A rail joint structure including rails 100 having flat head-fishing bearings and high-tensile bolt-clamping means, splice bars having flat head-fishing bearings designed to engage the flat head-fishing bearings of the rail heads and also having rail-head bearings conforming in contour to those of the head-fillets of the rails, said high-tensile bolt-clamping means being adapted to rotate the splice bars out of contact with the rail head-fishing bearings into contact with the head-fillet bearings of the rails and operating thereafter to maintain said splice bars in load-bearing contact with said rail head-fillet bearings and out of contact with said flat head-fishing bearings. 110 115

3. A rail joint structure including rails having flat head-fishing bearings and high-tensile bolt-clamping means, splice bars having flat head-fishing bearings designed to afford loading engagement with the head-fishing bearings of the rail heads and also having rail-head bearings conforming in contour to those of the head-fillets of the rails, said high-tensile bolt-clamping means being designed to rotate the splice bars out 120 of contact with the flat rail head-fishing bearings into contact with the head-fillet bearings of the rails and operating thereafter to maintain said splice bar in load-bearing contact with said rail head-fillet 125 130

bearings and out of contact with said flat head-fishing bearings.

4. A rail joint structure including rails having flat head-fishing bearings and high-tensile bolt-clamping means, splice bars having a flat head-fishing bearings designed to engage the flat head-fishing bearings of the rail heads and also having rail-head bearings conforming in contour to those of the head-fillets of the rails, said high-tensile bolt-clamping means being designed to rotate the splice bars out of contact with the flat rail head-fishing bearings into contact with the head-fillet bearings of the rails and

operating thereafter to maintain said splice bars in loading engagement with said rail head-fillet bearings and out of contact with said flat head-fishing bearings.

5. A convertible joint bar provided at its head with a flat head-fishing bearing and with a rounded rail-fillet engaging element, and on its lower member with a pair of separate angularly related flange bearing faces, each of which is adapted to engage the flange of the rail.

In testimony whereof I hereunto affix my signature.

MCLEOD THOMSON.
